UNITED STATES PATENT OFFICE.

HENRIETTA WILMER LAWRENCE, OF BALTIMORE, AND HARRY J. LEISHERZ, OF FREDERICK, MARYLAND.

REVERSIBLE BROILER.

1,170,829.

Specification of Letters Patent.

Patented Feb. 8, 1916.

Application filed October 23, 1915. Serial No. 57,394.

To all whom it may concern:

Be it known that we, HENRIETTA W. LAWRENCE, a resident of the city of Baltimore and State of Maryland, and HARRY J. LEISHERZ, a resident of the city and county of Frederick and said State, both citizens of the United States, have invented certain new and useful Improvements in Reversible Broilers, of which the following is a specification.

This invention relates to that class of broilers wherein is employed a gridiron or analogous device by means of which meats, &c., can be reversibly supported in proximity to a fire in such a manner that either side of the food may be cooked by the direct action of the heat as desired.

More specifically, the invention concerns a broiler of the class mentioned adapted to be mounted within the broiling oven of a gas range, or the like, in proper relation to the burner or burners, whereby the bodily turning of the gridiron may be accomplished while it is supported within the oven.

The primary object of our invention is to provide a cheap, simple and efficient broiler which can be readily applied to or removed from the oven of an ordinary gas range, and in which broiler the gridiron can be reversed with facility to present either side thereof to the burner or burners of the oven, and this without changing the position within the oven of the structure on which the gridiron is mounted.

Another object of our invention is the provision of simple and efficient means whereby the gridiron supporting structure, when mounted within the oven, can be bodily raised and lowered within limits in order to adjust the positioned gridiron in respect to the burner or burners, as desired.

Generally stated our invention comprises a gridiron (or equivalent device) and a supporting structure therefor having upper bearing elements in spaced relation to each other horizontally, and a lower bearing element in a vertical plane between the others; the said upper bearing elements being constructed and arranged to support the gridiron at its longitudinal edges and thus maintain it rigidly in horizontal position beneath the burner or burners of an oven, and also to permit either or both sides of the gridiron to be readily released; and the said lower bearing element being of such char-

acter as to receive and support either of said sides when it is released and dropped, whereby the gridiron can be bodily turned and its longitudinal edges shifted into opposite engaging relation with the upper bearing elements.

The invention also comprises a broiler supporting structure having laterally projecting members adapted to be slid upon the spacing portions in the inner walls of the oven, said members being adjustable vertically in relation to the body of the structure in order to vary the horizontal level of said structure and the gridiron thereon within the oven.

The invention also comprises various novel features of construction and combinations of parts, all of which will be herein-after described and claimed.

In the drawings—Figure 1 is a front elevation of a typical form of apparatus embodying the principles of our invention, the apparatus being illustrated as mounted within the broiling oven of an ordinary gas range. Fig. 2 is a similar view, showing the broiler rack or gridiron in different positions which it is caused to assume during the reversing operation, and also showing a variation in the position of the lateral projections of the supporting structure. Fig. 3 is a horizontal section as on the line 3—3 of Fig. 1. Fig. 4 is a transverse vertical section through the apparatus as on the line 4—4 of Fig. 3.

Referring to the drawings, 10 designates a broiler rack or gridiron of appropriate construction. In the present instance it comprises a substantially rectangular frame 11 and upper and lower grid sections 12, 13, respectively, suitably spaced on the frame and adapted to receive and clamp between them the steak, &c., to be broiled. The lower grid section is permanently affixed to the longitudinal bars of the frame, and the upper section is hinged to one of said bars, as at 14, so that it may be opened, and closed similarly to the cover of a book. A notched hook 15 is pivoted on the opposite bar of the frame 11 in such position that it may be readily engaged with the proximate part of the hinged section so as to lock the latter temporarily in closed position. This hook is preferably provided with a plurality of notches, as 16, in order that the hinged section may be locked in different positions of adjustment relative to the other section as 11.

occasion may require. The grid sections in the form illustrated are of less length than the interior of the interposed frame in order that the end portions of the longitudinal side bars 5 beyond said sections shall provide supports for the rack or gridiron when it is mounted and operated upon the structure now to be described.

17 designated two corresponding skeleton members in each of which are formed two upwardly diverging cam surfaces 18, 18^a which coöperate with the outer end portions of the side bars of the frame 11 and efficiently support and guide the gridiron when 15 it is being reversed, as will presently be explained. These cam members, as they may be termed, are rigidly held in spaced relation to each other by appropriate stretcher or tie-rods 19, the whole constituting a substantial supporting and reversing structure 20 for the gridiron.

Adjacent to the respective limbs of the cam members 17 are latch-like bearing elements which are constructed and arranged 25 normally to engage the opposing outer end portions of the side bars of the gridiron frame and thus support the gridiron in horizontal position across the top of the structure; the upper ends of the limbs of the respective members being provided with inwardly projecting shoulders 20 which constitute abutments for the opposing portions of the side bars of the gridiron frame, when it is supported by the bearing elements. In 30 the present instance the said bearing elements comprise two pairs of upwardly projecting latches or pawls, 21, 22, respectively, having their upper ends inwardly notched as at 23 to engage and support the opposing 35 side bars of the gridiron frame. Each pair of pawls is affixed to a rod 24 which is pivoted in and between the corresponding limbs of the cam members. Encircling each rod at or near one end thereof, is a spring 25 40 whereof one end is secured to the rod and the other end to the proximate member 17, in order that the torsional action of the spring on the rod shall tend to maintain the pawls in their normal of frame-engaging position.

50 The crotches 26 of the cam surfaces of the members 17 are disposed in a vertical plane intermediate the upper latch-like bearing elements, and the curvature or angularity of the said surfaces is such that if one side bar 55 of the frame of the horizontally supported gridiron be freed from the proximate pawls, as 21, that side of the gridiron will drop by gravity and the outer end portions of the freed bar will glide upon the corresponding 60 cam surfaces 18, opposed thereto until such portions impinge against the lower bearing element constituted by the medially disposed crotches; whereupon, by manual operation of the gridiron, its rotary movement may be 65 continued until the device is inverted in

which case the longitudinal bars of the gridiron frame will be engaged and supported by the pawl bearing elements at the respective sides of the structure. In other words, the gridiron in its bodily descent will turn 70 on the notched ends of the pawls 22 as an axis until the released bar of the gridiron frame impinges against the crotches, as illustrated by the full lines in Fig. 2; then the gridiron may be rocked or tilted upon 75 the crotches as an axis until the other or upper bar of the gridiron frame is engaged by the pawls 21, as indicated by the dotted oblique lines at the left in Figs. 1 and 2, and then, finally, the gridiron may be bodily 80 swung upward upon the pawls 21 as an axis until the bar at the free edge of the gridiron frame is engaged by the pawls 22, as indicated by the dotted horizontal lines in Fig. 2. In the downward and upward swinging 85 movements of the gridiron upon its respective bearings, as axes, at the top of the structure the opposing cam surfaces 18, 18^a efficiently support and guide the gridiron; it being noted that the latter in its rotary sweep 90 travels bodily within the relatively stationary structure. By a repetition of the operation just described the gridiron may be again reversed, and so on.

One of the pawls 21, namely, that at the front, is preferably provided with a handle extension 21^a whereby the attached rod and pawls may be conveniently manipulated to release the engaged edge of the gridiron frame; and one end of this frame, namely the front end, is also preferably provided with a projection 27 which is adapted to receive a suitable handle (as 27^a) to facilitate the handling of the gridiron.

The supporting and reversing structure 105 for the gridiron is provided with laterally-disposed wing-like projections, preferably in the nature of bars 28, which are adapted to be slid upon the supporting ledges 29 (or grooves) on the inner walls of the 110 broiler oven, as 30, of a gas range for example, and thus support the structure horizontally below the usual gas burner or burners 31. In order that the said structure and its appurtenances can be readily 115 adjusted vertically, and thus vary the proximity of the gridiron to the flame or flames from the burner or burners, as may be required, and this without necessitating the removal of the structure from the oven, we prefer to hinge the bars 28 to the cam members 17, and provide means whereby the outer ends of such bars can be conveniently swung up or down, to a greater or less extent as desired. A preferred form 125 of adjusting means for the bars includes downwardly and upwardly projecting arms 32, 33 on the respective bars 28; a link 28^a connecting said arms; a downwardly extending handle arm 34 on one of the bars, 130

and a segmental toothed rack 35 fast on side is manually swung to the median position, and the gridiron is thus free to be removed from the oven.

5 and a segmental toothed rack 35 fast on side is manually swung to the median position, and the gridiron is thus free to be removed from the oven.

5 predetermined notch in the rack. When the handle is actuated to raise or lower the bar 28 to which it is connected, a similar movement is transmitted through the arm and link connection to the opposite 10 bar, the two bars perform correspondingly moving and thus bodily raising or lowering the structure within the oven as the case may be. (See Fig. 2.)

15 The lower portions of the cam members of the structure may, if desired, be provided with extensions 36 having respectively inturned hooks 37 appropriately spaced and arranged to receive and support the usual drip pan 38. In deep ovens this 20 pan supporting arrangement is advantageous, but ordinarily the pan may rest directly on the bottom of the oven.

25 The operation of the typical apparatus above described is briefly as follows: The supporting and reversing structure is first slid into the oven in proper relation to the burner or burners. Then the drip pan is applied to the structure or imposed on the bottom of the oven, as desired. The steak, &c., is then clamped between the sections 30 of the gridiron and a handle (as 27^a) is attached to the latter. The gridiron is then entered endwise into the structure in a vertical position, with one of the longitudinal side bars of the gridiron resting in the crotches of the cam members. The upper edge of the gridiron is then allowed to swing over until the upper bar of its frame enters the notches of the pawls 21 as indicated by the dotted lines in Fig. 1. Then by a simple twist of the handle in the direction indicated by the arrow in Fig. 1, the lower edge of the gridiron is swung up 35 into engagement with the pawls 22, the latter thus, in conjunction with the pawls 21 maintaining the gridiron in horizontal position beneath the burner or burners. The handle 27^a is then removed from the gridiron, the oven door is closed and the 40 broiling commences. After a proper lapse of time the door is opened and the handle is again applied to the gridiron. The lower end of the long pawl 21 is manipulated to release the side of the gridiron frame engaged therewith, and permit that side to fall to the bottom of the structure and the gridiron thence to be swung to 45 reversed position as previously described, thus presenting the opposite side of the steak, &c., to the flame. This operation is 50 repeated until the broiling is finished, whereupon the long pawl 21 is again manipulated to release the proximate side bar of the gridiron frame. This side drops 55 to the bottom of the structure, the opposite

60 side is manually swung to the median position, and the gridiron is thus free to be removed from the oven.

65 It is to be understood that the apparatus herein shown and described is merely 70 illustrative of a preferred form of embodiment of our invention, and hence the apparatus may be structurally modified without departing from the principle of the invention. For example, we do not 75 intend to limit ourselves to the use of a "gridiron" in the specific sense of the term, as any appropriate form of equivalent food holder may be substituted therefor; nor do we wish to limit ourselves to 80 the use of the particular cam guides and supports shown as the same may obviously be modified as to form and arrangement. In one aspect of the invention those portions of the cam guides above the lower 85 bearing constituted by the "crotches" may be omitted, and the bearing portions of the upper pawls may be hook-shaped or otherwise fashioned so as to embrace the proximate sides of the gridiron frame, and thus 90 prevent the accidental release of either side of the gridiron from its pawls during the swinging of the other or released side of the gridiron toward or from the lower bearing as the case may be. Other structural 95 changes within the scope of the invention will suggest themselves in the light of the present disclosure.

We claim as our invention—

1. A reversible broiler comprising a grid- 100 iron and a supporting structure therefor having two upper bearing elements in spaced relation to each other horizontally, or substantially so, and a lower bearing element in a vertical plane between the upper bearing 105 elements.

2. A reversible broiler comprising a grid- 110 iron and a supporting structure therefor having two upper bearing elements in spaced relation to each other horizontally, or substantially so, a lower bearing element in a vertical plane between the upper bearing elements, and guide means for the gridiron in its travel between the lower and the upper bearing elements. 115

3. A reversible broiler comprising a grid- 120 iron and a supporting structure therefor having two upper bearing elements in spaced relation to each other horizontally, or substantially so, a lower bearing element in a vertical plane intermediate the upper bearing elements, and cam surfaces diverging from the lower bearing element toward the respective upper bearing elements.

4. A reversible broiler comprising a grid- 125 iron, a supporting structure therefor having upwardly diverging cam portions and movable bearing elements for supporting the gridiron substantially horizontal at the upper part of the said cam portions, the crotch 130

of said portions affording a bearing element for the gridiron when either movable element is removed therefrom.

5. A reversible broiler comprising a gridiron, a supporting structure therefor, spring-pressed bearing pawls normally positioned on said structure to support the gridiron substantially horizontal, a bearing element for the gridiron located below and in a vertical plane between the said pawls, and guide means for the gridiron in its travel between the lower bearing element and the upper bearing pawls.

6. A reversible broiler comprising a gridiron, a supporting structure therefor having upwardly diverging cam portions, spring-actuated bearing pawls normally positioned to support the gridiron substantially horizontal at the upper part of the said cam portions, the crotches of said portions affording a bearing element for the gridiron when the pawls are removed from either side of the gridiron.

7. A reversible broiler comprising a gridiron, a supporting structure therefor including cam members, tie-rods connecting the same in spaced relation to each other, pivot rods between said members, notched bearing pawls on the rods, and springs tending to maintain the rods and their pawls normally in active position.

8. A reversible broiler comprising a gridiron having a handle-receiving portion, a supporting structure having relatively movable gridiron bearing elements in spaced relation to each other horizontally, and a lower relatively stationary gridiron bearing ele-

ment arranged below and in a vertical plane between the said movable elements.

9. A reversible broiler comprising a gridiron and a supporting structure therefor having lateral projections, and means for simultaneously adjusting said projections vertically in relation to said structure.

10. A reversible broiler comprising a gridiron and a supporting structure therefor, said structure having pivoted thereto laterally-disposed projections, and means for swinging said projections vertically on their respective pivots and securing them in positions of adjustment.

11. A reversible broiler comprising a gridiron and a supporting structure therefor, said structure having laterally projecting wing members pivoted thereto, swinging adjusting means, including locking devices, connected with one of said members, and operative connection between the two members whereby they are simultaneously adjusted by actuation of said swinging means.

12. In a reversible broiler, a gridiron comprising a substantially rectangular frame, two grid sections spaced apart on the frame, one section being permanently affixed to the longitudinal side bars of the frame and the other section being hinged to one of said bars, and a latch for the hinged sections, said grid sections being of less length than the interior of the frame whereby the outer ends of the said side bars provide guiding and supporting portions for the gridiron.

HENRIETTA WILMER LAWRENCE.
HARRY J. LEBHERZ.
